US00D702547S

(12) **United States Design Patent**
Akana et al.

(10) **Patent No.:** US D702,547 S
(45) **Date of Patent:** ** Apr. 15, 2014

(54) **PACKAGING**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/430,551**

(22) Filed: **Aug. 27, 2012**

Related U.S. Application Data

(63) Continuation of application No. 29/418,215, filed on Apr. 13, 2012, now Pat. No. Des. 668,143, which is a continuation of application No. 29/369,022, filed on Sep. 1, 2010, now Pat. No. Des. 658,492.

(57) **CLAIM**

The ornamental design for packaging, as shown and described.

DESCRIPTION

FIG. 1 is a top perspective view of a packaging showing our new design;

FIG. 2 is a bottom perspective view thereof;

FIG. 3 is a front view thereof, the rear view being a mirror image thereof;

FIG. 4 is a side view thereof, the other side view being a mirror image thereof;

FIG. 5 is a top view thereof;

FIG. 6 is a bottom view thereof;

FIG. 7 is another top perspective view thereof with the cover in an open position;

FIG. 8 is an exploded view of the packaging of FIG. 1;

FIG. 9 is a bottom perspective view of the packaging of FIG. 1 with the cover in an open position;

FIG. 10 is a front view thereof, the rear view being a mirror image thereof; and,

FIG. 11 is a side view thereof, the other side view being a mirror image thereof.

The shade lines in the Figures show transparency, and not surface ornamentation.

The broken lines show portions of the electronic device which form no part of the claimed design.

1 Claim, 11 Drawing Sheets
